UNITED STATES PATENT OFFICE.

CARL R. HELLSTROM, OF MINNEAPOLIS, MINNESOTA.

BAG HOLDER.

1,424,017.

Specification of Letters Patent. Patented July 25, 1922.

Application filed January 23, 1922. Serial No. 531,238.

To all whom it may concern:

Be it known that I, CARL R. HELLSTROM, a citizen of the United States, residing at Minneapolis, in the county of Hennepin 5 and State of Minnesota, have invented certain new and useful Improvements in Bag Holders, of which the following is a specification.

The invention relates to paper bag holders, 10 and has as an object the provision of a device of this nature which will receive paper bags without special preparation of the bags and which will hold them in readily accessible position in any position of the holder,

15 A further object of the invention is the provision of a device of this nature which may be placed in an inverted position upon the under side of a counter top in a vertical position against a wall, or in a reclining 20 position upon a counter, and which will hold any kind of paper bag in such a manner as to make them instantly available.

Illustrative embodiments of the invention are shown in the accompanying drawings, in 25 which

Fig. 1 is a front elevation;

Fig. 2 is a rear elevation;

Fig. 3 is a horizontal section on line 3—3 of Fig. 2 of one form of the device;

30 Fig. 4 is a side elevation;

Fig. 5 is a vertical longitudinal section of the form shown in Fig. 4, showing a modified form;

Fig. 6 is a perspective view of the form 35 shown in Fig. 1 modified to hold different forms of bags;

Fig. 7 is a front elevation of the form shown in Figs. 1 and 6, illustrating its use in an inverted position;

40 Fig. 8 is a side elevation of the same form of the invention, showing its use upon the underside of a surface, as a counter top;

Fig. 9 is a detail rear elevation of a modification;

45 Fig. 10 is a section on 10—10 of Fig. 9, showing the device secured in place for use;

Fig. 11 is an end view upon a reduced scale showing a series of the holders assembled upon a surface such as a counter;

50 Fig. 12 is a detail plan view showing the casing in section illustrating a modification upon a reduced scale.

As shown in Fig. 1, the invention comprises a casing 1 within which the bags may 55 be placed, the casing being provided with flanges 2 at the rear edges of the side por-

tions, and with flanges 3 at the rear edges of the ends, which latter flanges may be utilized to secure the device in place in some positions. The rear side of the casing is 60 freely open for the insertion of bags.

For a purpose to be described a diagonal slot 4 is formed from the rear edge towards the front edge and slanting away from the adjacent end of the casing. Preferably, the 65 material which is removed to form the slots 4 is turned up, as at 5, so as to provide a smooth edge for the slot. The lower front portion of the casing is omitted to leave an opening through which the bags may be 70 removed. To provide an edge across which the bag may be drawn upon its removal to prevent more than one bag being removed at a time, the upper edge 8 of the front opening is preferably deflected inwardly. 75 Such deflection provides an excess of pressure between the outer two bags in the casing at this point, and reduces the overall friction between their surfaces so that but one bag will be removed at a time.

To retain the lower end of the bag when the form of bag shown in Figs. 1 to 5 inclusive is to be delivered, a rod 7 is passed through openings in the side walls of the casing and may be retained in any suitable 85 manner as by means of a nut, as shown.

To crowd the bags in the casing forward a rod 10 is shown projecting through the slot 4 at each side of the casing and retained in endwise position by means of its upturned 90 ends 11. When the device is to be used against a vertical surface the entire weight of the casing and bags may be carried by means of a strap 16 passed through a slot 18 adjacent the flange 3 and secured to the 95 rod 10. The strap 16 may have openings 17 at its upper end which may be placed over the head of a screw or nail in a wall. The weight of the device and the contained bags pressing the rod 10 upwardly in 100 inclined slot 4 will ensure that the bags will at all times be pressed against the front of the casing and against the rod 7. This point of pressure being slightly above the rod 7 and even when opposite this rod, being exerted in an upward and outward direction will cause the bags to bulge so as to throw the bottom of the bag outwardly in a position to be readily grasped. When the bag is removed the projecting edge of the 110 bottom will be pulled downwardly and the leverage of its removal from the front of

the pile will make the lower end of the bag remaining in the case kick up slightly so as to effectively project the upper edge of the bottom of the next bag into accessible position.

If the form of the device shown in Figs. 1 and 2 is inverted as shown in Fig. 7, and suspended by means of a screw or nail through an opening in the flange 3 the weight of the strap 16 and the rod 10 will be effective to force the bags to the front of the casing.

In the form of the device shown in Figs. 5, 9 and 10 a strap 13 is shown extending across the rear of the casing and having its ends turned about the flanges 2. The strap 9, corresponding to the strap 16 already described, is shown as secured to the center of the strap 13 at one end, and as turned about the rod 10 at its other end. The strap 13 may be secured to a wall as indicated in Fig. 5, and thus the weight of the casing and the bags therein may be supported upon the rod 10 and the strap 13, which latter will be concealed.

The ends of the strap 13 are so turned about the flanges 2 as to be readily slidable thereon to provide for the motion of the rod 10 in the slot 4. To remove this form of the device from its support the casing is forced upwardly until the rod 10 leaves the slot 4 then the bottom end of the casing is drawn outwardly so that the rod 10 will not enter the slot 4 then the casing is pulled downwardly until the ends 15 of the strap 13 leave the upper end of the flanges 2. The casing may then be charged with bags and replaced by the reverse movement. The action of this form of the device is exactly similar to that of the form shown in Figs. 1 and 2. When the device is to be used for the form of bags which have no projecting edge at its bottom the rod 7 is removed and a pin 21 shown in Fig. 6 is placed in an opening 45 preferably slightly above the opening provided for the rod 7. Also the casing is provided with a depression in its exposed front edge, as shown at 6, in Fig. 6. The bags of this form are then removed by grasping the edge in the depression 6, which edge will be thrown outwardly by the action of the rod 10 already described.

Either form of the device may be utilized for a position upon the under surface of a counter top or ceiling 22, as shown in Fig. 8, by omitting the rod 10 and securing the casing in place by means of the flange 3.

When thus used the bags will be brought to the front of the casing by gravity and the edge which is to be grasped will be projected by the leverage action of the removal of the preceding bag about the rod 7 as already described.

In most instances a plurality of sizes of paper bags are kept at hand, and therefore

a holder will be desirable for each size. Figure 11 shows a form of rack which may be utilized for such a plurality of devices. In this form the rod 19 supported in brackets 20 mounted upon any desirable base is shown as passing through all of the slots 5 in each of the casings 1, thus taking the place of a rod 10 for each casing. Any casing may be removed from the rod by merely lifting the same off from the slot 4 when it is necessary to replenish the bags contained therein.

A form of rack which may be utilized to carry a plurality of holders is illustrated in Fig. 12 in which a plate 23 may be utilized to mount all of the casings. A portion 24 of the plate may be struck upwardly and formed into one portion of a hinge, and a strap 25 may have the complementary hinge portion formed thereon, and may be joined to the portion 24 by means of a pintle 26. The lower end of the strap 25 may be secured to the rod 10, which will act in the usual manner. Other portions of the plate 23 may be struck upward so as to provide guides 27-28 which will overlap the flanges 2 to hold the casings 1 against the plate. The removal of the casings for replenishment in this form of the invention would be precisely similar to that with the form of the invention shown in Figs. 4, 5 and 9.

The device is found to hold paper bags so as to be instantly accessible with a quick stripping action of the hand. Being enclosed at its top the edges of the paper bags which give access to the interior thereof are protected in a sanitary manner. The bags will not be handled at all after being removed from their original package and need not be manipulated in any manner to prepare them for insertion in the holder, thereby preserving to the utmost sanitary conditions.

Minor changes may be made in the physical embodiment of the invention without departing from its spirit.

I claim:

1. A dispensing device comprising, in combination, a casing, an opening in the front of the casing, a bar adjacent one end of the opening to retain the ends of objects to be dispensed, a depressed edge at the opposite side of the opening, and means in said casing to move said objects toward said opening.

2. A dispensing device comprising, in combination, a casing having an opening adjacent one end of its front, means in said opening to retain the ends of objects to be dispensed, a diagonal guide-way carried by the side walls of said casing opposite said opening, means working in said guide way to press objects towards said opening.

3. A dispensing device comprising, in combination, a casing having an opening in one end of its front wall, means in said

opening to retain the ends of objects to be dispensed, diagonal guide-ways in the side walls of said casing, adjacent said opening, a rod working in said guide-ways and adapted by the action of gravity to force the objects in said casing towards said opening.

4. A dispensing device comprising, in combination, a casing having an opening adjacent one end of its front wall, means to retain the end of objects to be dispensed, guide-ways in the side walls of said casing opposite said opening extending from the rear edge of said side walls towards the front edges thereof and toward the opposite end of the casing, a rod working in said guide-ways, and means attached to said rod whereby the casing and contents may be supported from said rod whereby the action of gravity will move the rod in said guide-ways to press the objects towards the front of the opening.

5. A dispensing device comprising, in combination, a casing having an opening adjacent one end of the front thereof, diagonal guide-ways extending from the rear edge of the sides of said casing adjacent said opening, a rod working in said guide-ways, a strap secured to said rod and means for supporting said casing by said strap in such a manner that the rod will be pressed toward the front of the casing in said guide-ways by the action of gravity.

6. A dispensing device comprising, in combination, a casing having an opening adjacent one end of the front thereof, diagonal guide-ways upon the sides of said casing extending upwardly and forwardly, a rod working in said guide-ways, a strap secured to said rod, supporting means having guiding portions, said strap secured to said supporting means, and means upon said casing coacting with said guiding means and slidably relative thereto whereby the weight of the casing and contents may press said rod toward the front of the casing in said guide-ways.

7. A dispensing device comprising, in combination, a casing having an opening in the front thereof, members projecting from the sides of said casing, a supporting member having ways co-acting with said projecting members, said supporting member adapted to be attached to a surface, guide-

ways upon the sides of said casing extending diagonally upward and forwardly, a rod 55 traveling in said guide-ways, a strap secured to said rod and to said supporting member whereby the weight of the casing and contents may press said rod toward the front of the casing.

8. A dispensing device comprising, in combination, a plate having a plurality of ways thereon, a plurality of casings having projecting portions adapted to travel in said ways, each casing having an opening in the front thereof, upwardly and forwardly extending guiding means in the sides of each casing, a rod in each casing adapted to travel in said guiding means, and a strap connected to each of said rods and pivotally 70 connected to said plate whereby the weight of the casings and contents may cause the respective rods to be pressed towards the front of the casing.

9. A dispensing device comprising, in 75 combination, a casing having an opening in the lower portion of its front and slots extending from the rear edge of each side forwardly and upwardly therein, the rear of said casing being open, a rod extending 80 through said slots transversely of the casing and having retaining means at its ends to prevent longitudinal movement, a strap secured to said rod, means for securing said strap to a supporting structure whereby the 85 weight of the casing and contents will be supported upon said rod and will cause the same to move toward the front of the casing.

10. A dispensing device comprising, in combination, a casing having an opening in 90 the lower portion of its front and slots extending from the rear edges of each side forwardly and upwardly therein, the rear of said casing being open, a rod extending 95 through said slots transversely of the casing and having retaining means at its ends to prevent longitudinal movement, a strap secured to said rod, means for securing said strap to a supporting structure whereby the weight of the casing and contents will be 100 supported upon said rod and will cause the same to move toward the front of the casing, means extending into said front opening to retain the lower ends of articles to be dispensed.

CARL R. HELLSTROM.
